CLAIM

The ornamental design for a display screen or portion thereof with a graphical user interface as shown and described.

DESCRIPTION

This application is related to the following commonly owned co-pending patent applications: U.S. application Ser. No. 18/363,236, entitled "KENO EMPLOYING MIRRORRED DRAWN SPOTS"; U.S. application Ser. No. 29/909,119, entitled "DISPLAY SCREEN OR PORTION THEREOF WITH A GRAPHICAL USER INTERFACE"; and U.S. application Ser. No. 29/909,121, entitled "DISPLAY SCREEN OR PORTION THEREOF WITH A GRAPHICAL USER INTERFACE".

FIG. 1 is a front view of a display screen or portion thereof with a graphical user interface of one embodiment of our new design; and,

FIG. 2 is a front view of a display screen or portion thereof with a graphical user interface of another embodiment of our new design.

The dashed broken line perimeter in the drawings illustrate a display screen or portion thereof and forms no part of the claimed design.
